L. LORENZ

BURNING IN MACHINE

Filed March 26, 1926

INVENTOR
Louis Lorenz

Soltan H. Blachefsky
ATTORNEY

UNITED STATES PATENT OFFICE.

LOUIS LORENZ, OF NEW YORK, N. Y.

BURNING-IN MACHINE.

Application filed March 26, 1926. Serial No. 97,590.

This invention relates generally to an apparatus for etching plates used in connection with the photoengraving and allied processes.

5 The invention having more particular reference to a novel type of apparatus for use in treating etching plates composed of metal sheets with selected portions of a side thereof covered with erosive resisting coating.

10 The invention has for an object the provision of an improved apparatus of the class described embodying novel construction and arrangement of parts.

15 For further comprehension of the invention, and of the objects and advantages thereof, reference will be had to the following description and accompanying drawing, and to the appended claims in which the 20 various novel features of the invention are more particularly set forth.

Fig. 1 of the drawing shows a front elevational view of my improved apparatus.

Fig. 2 shows a side elevational view 25 thereof.

Fig. 3 shows a rear elevational view thereof.

Fig. 4 shows longitudinal view of the tray and heating device, as used in connection with my improved apparatus.

30 Fig. 5 shows a top plan view of the heating device as used in connection with my improved device.

Fig. 6 shows a longitudinal sectional view 35 taken on the line 6—6 of Fig. 5.

As here embodied my improved apparatus comprising a stand or frame work having upright members 10 with base portions 11, attached thereto at their lower extremities, 40 and cross supporting members 12 conveniently located, and diagonal braces 13. The dome 14, preferably of sheet metal, is attached to the upper extremities of the upright members 10, and has a centrally 45 located protruding portion 14', of hollow construction. The above described construction being such as will support the hereinafter mentioned and described elements of my improved apparatus.

50 The tray consists of a frame 16, preferably angle shaped metal, to support a bottom 17, and upper extended sides 18. It being understood that the above mentioned construction is such as will accomodate the

etching plates to be treated immersed in a 55 suitable liquid.

The heating device consists of a frame 19, of any suitable metal, having terminal bars 20 located crosswise thereof, adjacent to and supported from the frame 19 by depending 60 bracket 21, of any suitable insulating material. The supporting members 22, preferably angle shaped metal, located crosswise of the frame 19, are suitably spaced therein, and supported therefrom, as at 23, and have 65 attached thereto supporting pieces 24, of any suitable insulating material, depending upward therefrom, and provided with a plurality of apertures spaced therein and adapted to receive the heating elements 25, 70 preferably of nichrome wire, close wound, attached to the said terminal bars 20, as at 26. It being understood that the terminal bars 20, having suitably attached thereto the electric wires 27 and 28 which are suitably 75 attached to the ammeter-voltmeter 60, the fuses 61, and the switch 62, conveniently attached to the front of the said frame work, and that the switch 62 is connected to a suitable, convenient source of electric current. The latter mentioned elements being 80 those of ordinary, common construction such as generally used for apparatus of this nature, any suitable convenient source of electric current. The above mentioned 85 construction being such as will permit the said current to heat the heating elements 25, so as to heat the said etching plates and the said liquid, in the heretobefore mentioned tray, to the desired temperature, so 90 as to erect the said etching plates by burning in the said liquid as may be required.

The above mentioned tray, and the above mentioned heating device, have attached thereto, and depending therefrom pins 29, 95 adapted to receive sockets 30, formed in the blocks 31 and 32, which are attached as at 33 to the cross supporting members 12 of the said frame work. The above mentioned construction being such as will allow the 100 said tray and the said heating device to pivot. It being understood that the said heating device is located a suitable distance above the said tray.

The said heating device has pivotally attached at or near its center a lever 34, as at 35, which is also pivotally attached, as at 36, to a lever 37, which is also pivotally

attached, as at 38, at or near the center of the said tray. The said lever 37 has a protruding portion 39, at a right angle thereto, and adapted to engage the said lever 34, 5 when the said heating element has been pivotally raised the desired amount, so as to pivotally raise the said tray and the desired amount when the said tray is pivotally raised higher. The above mentioned mechanism 10 being provided to facilitate the placing of and removal of the etching plates before and after treatment, and also to facilitate the inspection of the said heating device.

15 It will be further understood that a flexible member 40, preferably suitable steel tape, is attached at one extremity, to the free extremity of the said tray, as at 41, and is extended over pulleys 42, preferably of 20 flat, flanged construction, and rotatively mounted in the said frame work, the said flexible member 40 being attached at its other extremity, as at 43, to a suitable counterweight 44, located in one of the said upright members 10, as clearly shown in the accompanying drawing. The above described construction being such as will decrease the effort required to pivotally raise the said tray and the said heating device.

25 30 It will be further understood that the electric motor 46, is located in the said dome 14, and supported therein by supporting members 47, attached to the uprights 48, which are carried by the said frame work.

35 The electric motor 46 is adapted to operate with its shaft 49 in a vertical position, the fan 50, of suitable size, is attached to the said shaft 49. It being understood that the electric motor 46 is suitably connected to 40 any suitable convenient source of electric current, and that the said fan 50 is located directly below the said protruding portion 14' of the dome 14. The above described construction being such as will permit the 45 fan 50 when rotated or revolved by the electric motor 46 to create a partial vacuum, which will draw the heat and fumes from the said tray and from the said heating device through the protruding portion 14', which may be suitably connected to pipes 50 or the like leading outside the building, housing my improved apparatus.

While I have above described the preferred form, construction and arrangement 55 of the several elements employed, it will be understood that the device is nevertheless, susceptible of considerable modification therein, and I therefore reserve the privilege of resorting to all such changes as may be fairly embodied within the spirit and scope of the invention as claimed.

Having thus described my invention, what I claim as new and desire to protect by Letters Patent of the United States is as 60 follows:—

1. An apparatus for treating etching plates composed of metal sheets with a selected portion of a side thereof covered with erosive resisting coating, comprising a frame work adapted to pivotally support a tray 70 and a heating device.

2. An apparatus for treating etching plates composed of metal sheets with a selected portion of a side thereof covered with erosive resisting coating, comprising a frame work adapted to pivotally support a tray 75 and a heating device, said heating device located below the said tray, said heating device attached to the said tray and pivoted levers, so as to pivotally raise the said heating device when the said tray has been partly raised.

3. In a device of the class described a frame work adapted to support a dome having an extended hollow portion, an electric 85 motor operatively attached to a fan, said electric motor located in the said dome, said fan located directly below the said extended hollow portion of the said dome.

4. In a device of the class described a heating device consisting of a frame having terminal bars located crosswise thereof, adjacent to and supported from the said frame by depending brackets, supporting members located crosswise of the said frame and spaced therein, and supported therefrom, and having attached thereto supporting pieces depending upward therefrom, and provided with a plurality of apertures spaced therein, and adapted to receive heating elements attached to the said terminal bars.

5. In a device of the class described, a tray and a heating device, having attached thereto and depending therefrom socket members adapted to receive sockets, formed in blocks, attached to cross supporting members of a frame work.

6. In a device of the class described, a tray having pivotally attached at its center, a lever, said lever also pivotally attached to a second lever pivotally attached, at the center of a heating device, the said second lever having a protruding portion at a right angle thereto, adapted to receive the said lever when the said tray has been pivotally raised a desired amount, so as to pivotally raise the said heating device, when the said tray is pivotally raised higher.

7. In a device of the class described, a tray and a heating device, having attached thereto and depending therefrom socket members adapted to receive sockets, formed in blocks, attached to cross supporting members of a frame work, said tray having pivotally attached at its center a lever, said lever also pivotally attached to a second lever pivotally attached, at the center of a heating device, the said second lever having a protruding portion at a right angle 130

thereto, adapted to receive the said lever when the said tray has been pivotally raised a desired amount, so as to pivotally raise the said heating device, when the said tray is 5 pivotally raised higher.

8. In a device of the class described, a flexible member attached at one extremity to the free extremity of a tray, said flexible member extended over pulleys, rotat- 10 ively mounted in a frame work, said flex-

ible member attached at its other extremity to a counter weight slidably mounted in guides attached to the said frame work, said tray and a heating device pivotally attached to the said frame work, and attached by piv- 15 oted levers to each other.

In testimony whereof I have affixed my signature.

LOUIS LORENZ.
